UNITED STATES PATENT OFFICE.

AMBERSION McCULLEY, OF MONROE, WISCONSIN.

MOLD.

Application filed November 11, 1922. Serial No. 600,278.

To all whom it may concern:

Be it known that I, AMBERSION McCULLEY, a citizen of the United States, residing at Monroe, in the county of Green and State of Wisconsin, have invented certain new and useful Improvements in Molds, of which the following is a specification, reference being had to the accompanying drawings.

This invention relates to molds, and has for its object to provide a mold capable of molding tubular devices such as cisterns, cesspool necks, etc.

It is also an object of the invention to provide a mold of this character wherein the walls of the mold can be readily removed from the product, after the material has set, without danger of injuring the product.

It is a further object of the invention to provide a mold of this character including an inner and outer wall, said walls cooperating to provide an endless chamber for the reception of the material used in the formation of the product.

It is still a further object of the invention to provide a mold of this character particularly adapted for molding endless or tubular objects and wherein each wall of the mold is separable to permit removal of the walls of the mold from the product independently of each other.

With these and other objects in view, the invention consists in the improved construction and arrangement of parts to be herein-after more particularly described, fully claimed and illustrated in the accompanying drawings, in which:

Figure 1 is a top plan view of a mold constructed in accordance with an embodiment of the invention;

Figure 2 is a side elevation of the mold;

Figure 3 is a section taken on the line 3—3 of Figure 1 and showing the product in the mold;

Figure 4 is a detailed plan of the fastening means of the inner wall, and

Figure 5 is a perspective view of the product of the mold with a cover applied.

Referring to the drawings, 5 designates a base member which may be made of any suitable material, said base member having two annular series of openings for the reception of bracing pins 6 and 7, the purpose of which will be hereinafter described.

In connection with the base 5, an outer annular wall member 8 is provided. This wall member consists of a sheet of material,

preferably metal, split as at 9 to provide end portions 10 and 11. The end portion 10 is provided with cleats 12 which project a considerable distance beyond said end portion. The end portion 11, similar to the end portion 10, is provided with cleats 13 which project beyond said end toward the cleats 12. The projecting end portions of the cleats 13 are intended to be disposed inwardly of the cleats 12 and to engage the adjacent side edges of the cleats 12 so as to properly position the end faces of the end portions 10 and 11 and provide an endless annular wall when the mold is set up for use.

In order to reinforce the outer wall, the reinforcing bands 14 and 15 are provided, each band having ears 16 formed at their ends and provided with registering openings for the reception of a bolt 17. By this means it is impossible for the weight of the material to cause the wall to separate.

In connection with the outer wall 8, an inner annular wall 18 is provided, the inner wall being split as at 19 to provide end portions 20 and 21, the confronting end faces of said end portions being adapted to engage each other to provide an endless wall. In order that the end portions 20 and 21 of the wall 18 may be securely locked without requiring bands or like fastening means to be passed around the outer edge of the wall, there is provided novel fastening means. This fastening means comprises a keeper 22, said keeper having its end portion 23 extended at right angles to the keeper and provided with a recess 24, the end portion 23 extending inwardly of the annular wall 18. The keeper is secured to the end portion 21 of the wall adjacent the edge of said end portion. Carried by the end portion 20 inwardly of the edge of said end portion is a supporting member 25 having its end portion 26 offset and provided with an opening. A lever 27 has its end portion 28 pivoted to the offset portion 26. The portion 29 of said lever is also offset substantially in parallel relation to the offset portion 26 and again offset as at 30 to provide a latch member.

To operate the fastener, the portion 29 adjacent the latch 30 is engaged with the side of the end portion 23, to urge the end faces of the wall into engagement with each other. One of these latches is provided at the top of the wall and one at the bottom, the entire latch mechanism extending in

wardly of the wall so as to eliminate projections in the chamber of the mold.

In the use of the device, the outer annular wall 8 is placed upon the base 5 and the lower band 15 applied as well as the upper band 14, so as to urge the edges of the split portion 9 into engagement with each other. The pins 6 are then placed in the opening of the base to properly brace the outer wall. The inner wall is smaller in diameter than the outer wall and is intended to be placed within the outer wall in annular spaced relation to said outer wall to provide a mold chamber 31, said chamber being annular. After the inner wall has been placed in position, the fastening means is actuated to connect the ends of the wall. The pins 7 are then placed in the base so as to brace the wall from the inner face thereof. Concrete, cement or like material may then be placed in the chamber 31 to form the device A.

This mold is particularly adapted for the production of cisterns, cesspool necks and like devices. In Figure 5 is shown a perspective view of a cesspool neck and cover, the cover being made of the same material as the neck and reinforced with rods, one of said rods providing a handle; the handle being disposed centrally of the cover.

From the foregoing it will be readily seen that this invention provides a novel form of mold particularly adapted for use in the formation of cesspool necks, cisterns, or in fact, any device requiring a tubular body member. In addition to this, regardless of the fact that the product is annular, there is no danger of the product being damaged when the mold is being disassembled. This is accomplished by releasing and removing the bands 14 and 15, and separating the edges of the outer annular wall so as to permit the same to be readily removed. The inner wall may also be easily removed by actuating the fastening means to separate the ends and to permit said ends to be overlapped to decrease the diameter of the wall and thus permit the wall to be readily removed from the member A. All of these features are possessed by a device composed

of only a small number of simple parts 50 which may be easily assembled and disassembled.

What is claimed is:—

1. A mold comprising a base, a tubular outer wall disposed on the base, a tubular inner wall disposed on the base inwardly of the outer wall, each of said walls being split at one point, cleats carried by the edges of the split portion of the outer wall, the cleats of each edge engaging the opposite edge for holding said confronting edges of said split portion in engagement with each other to provide an even surface, reinforcing bands carried by the upper and lower portions of the outer wall, said bands being adapted to engage the outer cleats of the wall, means for securing said bands to said wall, and fastening means carried by the inner wall, said fastening means projecting from the inner surface of the inner wall, said inner wall being disposed in annular spaced relation to the outer wall to provide an endless mold chamber.

2. A mold comprising a base, a tubular outer wall disposed on the base, a tubular inner wall disposed on the base inwardly of the outer wall, each of said walls being split at one point, a pair of cleats carried by each of the edges of the split outer ring and projecting beyond said edges, the cleats of one edge being adapted to engage the adjacent cleat of the opposite edge to hold said edges in engagement with each other and prevent lateral movement of the split portions of the wall, bands carried by the upper and lower portions of the outer wall, said bands being adapted to engage one of the adjacent cleats of the outer wall to limit movement of said band, a keeper carried by one of the edge portions of the split inner wall, a fastener carried by the adjacent edge of the split inner wall, said fastener being adapted to engage the keeper to urge said edges into engagement with each other to provide an even surface at the split portion of the wall.

In testimony whereof I hereunto affix my signature.

AMBERSON McCULLLEY.
